UNITED STATES PATENT OFFICE.

FRANCIS J. HANRAHAN, OF RUPERT, PENNSYLVANIA.

ANGLE-COCK HANDLE.

Application filed September 15, 1925. Serial No. 56,510.

To all whom it may concern:

Be it known that I, FRANCIS J. HANRAHAN, a citizen of the United States, residing at Rupert, in the county of Columbia and

5 State of Pennsylvania, have invented a new and useful Angle-Cock Handle, of which the following is a specification.

By way of explanation, it may be stated that the handles of angle cocks, of the sort 10 used on freight and passenger cars, frequently break off, the results being of a more undesirable and time-consuming nature than might be expected upon superficial consideration. When the handle of an angle 15 cock breaks, the angle cock frequently must be taken out or repaired, not because the angle cock itself is radically out of order, or functionally inoperative, but simply because it has a broken handle, and cannot be 20 manipulated conveniently.

The laying up of expensive rolling-stock, merely for the purpose of repairing a valve handle, is an expensive proceeding, and, all 25 of the foregoing being understood, it may be stated that this invention aims to provide an auxiliary handle which may be applied readily to the main handle of an angle cock, when the main handle is broken, advantage being taken of some of the standard parts 30 of the main angle cock handle, in securing a firm mounting for the auxiliary handle, the auxiliary handle being so constructed that minor differences in the structure of the main angle cock handle will be accommodated.

35 It is within the province of the disclosure to improve generally and to enhance the utility of devices of that type to which the invention appertains.

40 With the above and other objects in view which will appear as the description proceeds, the invention resides in the combination and arrangement of parts and in the details of construction hereinafter described 45 and claimed, it being understood that changes in the precise embodiment of the invention herein disclosed, may be made within the scope of what is claimed, without departing from the spirit of the invention.

50 In the drawings:—

Figure 1 shows in side elevation, a standard form of angle cock, the valve handle of which has been broken off, the device forming the subject matter of this application being mounted in place on the broken han-

dle; Figure 2 is a top plan of the structure shown in Figure 1; Figure 3 is a section on the line 3—3 of Figure 2; Figure 4 is a section on the line 4—4 of Figure 2. 60

In order that the utility of the device forming the subject matter of this application may be understood clearly, and in order that it may be manifest how sundry old parts in a standard angle cock are given 65 new and added functions, it is necessary to describe at some length, a standard form of angle cock, notice being given at the point where the description of that which is old ceases, and the description of that which is 70 new begins.

In Figures 1 and 2 of the drawings, there is depicted the body 1 of an angle cock, the stem of the valve being marked by the numeral 2 and being secured within an arm 3 75 having lateral lugs 4, the arm being hinged at 5 to the head 6 of a main handle 7, the arm 3 having a depending projection 8 which works within a slot 9 formed by the extension 10 of an upstanding flange 11 on 80 the head 6 of the main handle 7, the head 6 of the handle 7 having internal wings 12, the head 6 being provided with depending projections 15 adapted to cooperate with side stops 14 on the body 1, the body having a 85 web 16 wherewith the depending projection 8 on the arm 3 is adapted to cooperate.

No novelty is claimed for the parts above enumerated, since they are shown in Figure 6 of Patent No. 1,015,856, granted on September 30, 1912, to Walter V. Turner of Edgewood, Pennsylvania, for sundry improvements in an angle cock device. Some of the parts above enumerated have new and added patentable functions, when considered in combination with the auxiliary angle cock handle now to be described. As to the operation of the specific angle cock described above, the reader is referred to the patent mentioned, in the event that he is not 90 a person sufficiently skilled in the art to understand the drawings of this present application at a glance.

In carrying out the invention, there is provided an auxiliary handle 17, which may be 105 inclined, as shown in Figure 1, to follow approximately, the slope of the nozzle 23 of the angle cock. At its inner end, the handle 17 has a socket 18, formed by two underlined fingers 19, the terminal edges of 110 which are separated to define a space which is shown at 24 in Figure 3. The inner end

of the auxiliary handle 17 is supplied with a fork 20. Assuming that the main handle 7 of the angle cock has been broken off, as shown in Figure 1, the broken main handle 5 is slid into the socket 18, the fork 20 resting on the head 6 of the main handle 7, and the ends of the fork 20 abutting against the upstanding flange 11 of the head 6, the extension 10 of the flange 11 being received in 10 the fork 20. The construction above described affords a very secure mounting for the auxiliary handle 17 and gives the parts 11, 6 and 10, new functions, in combination with the handle 17 and its fork 20. The handle 15 17 is held in place by a securing element 22, for instance, a cotter pin, the cotter pin extending downwardly through the auxiliary handle 17, through the broken main handle 7 which is drilled to receive the cotter pin, 20 and through the space which exists at 24 between the fingers 19 which form the socket 18, the arms of the cotter pin or securing element 22 being bent laterally, as in Figure 3, to engage the fingers 19. When the extremities of the fork 20 of the handle 17 engage the upstanding flange 11 of the head 6 of the main handle 7, there is a space 21 between the base of the fork 20 and the outer end of the extension 10 of the flange 25

11, and this enables the auxiliary handle 17 30 to be applied to devices wherein the extension 10 is somewhat longer than is shown in Figure 2 of the drawings.

What is claimed is:—

1. In a device of the class described, a cock comprising a body, a valve stem journaled in the body, an arm mounted on the stem and having a projection, a main handle including a head hinged to the arm and provided with a projecting portion defining a slot in 40 which the projection of the arm operates, and an auxiliary handle supported on the head and provided with a socket in which the main handle is mounted, the auxiliary handle having a fork receiving the projecting portion of the main handle. 45
2. A device of the class described, constructed as set forth in claim 1, and further characterized by the fact that the head of the handle has a flange of which said projecting portion of the head forms a part, the inner end of the fork abutting against said flange to space the base of the fork from said projecting portion. 50

In testimony that I claim the foregoing 55 as my own, I have hereto affixed my signature.

FRANCIS J. HANRAHAN.
